UNITED STATES PATENT OFFICE

114,432

DESIGN FOR A TIRE

George W. Anderson, Akron, Ohio

Application August 26, 1938, Serial No. 79,573

Term of patent 14 years

To all whom it may concern:

Be it known that I, George W. Anderson, a citizen of the United States, residing at Akron, in the county of Summit and State of Ohio, have invented a new, original, and ornamental Design for a Tire, of which the following is a specification, reference being had to the accompanying drawing, forming a part thereof.

In the drawing, Figure 1 is a fragmentary perspective view, partly in dotted lines, of a tire showing my new design;

Fig. 2 is an enlarged fragmentary sectional view, partly in dotted lines, taken substantially

on the line 2—2 of Fig. 1 illustrating the contour of the side wall design; and

Fig. 3 is an enlarged fragmentary elevational view, partly in dotted lines, of a portion of the tire side wall shown in Fig. 1, illustrating the details of the design.

The dominant feature of the design resides in the portion of the tire shown in full lines.

I claim:

The ornamental design for a tire, substantially as shown and described.

GEORGE W. ANDERSON.
